UNITED STATES PATENT OFFICE.

MARIAN HOLMES NEVIUS, OF NEW YORK, N. Y.

DESIGN FOR A TWINE-HOLDER.

48,649.

Specification for Design.

Patented Feb. 29, 1916.

Application filed November 11, 1915. Serial No. 60,979. Term of patent 3½ years.

To all whom it may concern:

Be it known that I, **MARIAN HOLMES NEVIUS**, a citizen of the United States, residing in the borough of Manhattan of the city of New York, in the State of New York, have invented a certain new and ornamental Design for a Twine-Holder, of which the following is a specification, reference being had to the accompanying drawings, forming a part hereof.

In said drawings, Figure 1 is a front elevation of a twine holder illustrating my new design. Fig. 2 is a view in side elevation thereof.

I claim—

The ornamental design for a twine holder as shown.

Signed this 9th day of November, 1915.

MARIAN HOLMES NEVIUS.
